United States Patent Office

Des. 177,615
Patented May 8, 1956

177,615

CARTON OPENING KNIFE

William F. Cralle, Charlotte, N. C., assignor to Independence Specialties Co., Inc., a corporation of North Carolina

Application November 21, 1955, Serial No. 38,965

Term of patent 14 years

(Cl. D22—3)

Fig. 1

Fig. 2

Fig. 3

Fig. 4

Fig. 5

Fig. 6

Fig. 1 is a side elevation of a carton opening knife embodying my new design;

Fig. 2 is a corresponding side elevation showing the knife blades partially opened;

Fig. 3 is an opposite side elevation, with respect to Figs. 1 and 2, in which the knife blades are shown fully opened;

Fig. 4 is a top plan view corresponding to Fig. 1;

Fig. 5 is a left end view corresponding to Fig. 3; and

Fig. 6 is a right end view corresponding to Fig. 3.

I claim:

The ornamental design for a carton opening knife, as shown.
